(57) **CLAIM**

The ornamental design for a plastic container, as shown and described.

DESCRIPTION

FIG. 1 is a top, front, and left side perspective view of a plastic container showing our new design;

FIG. 2 is top, rear perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a bottom plan view thereof;

FIG. 8 is a top plan view thereof;

FIG. 9 is a bottom, front, and left side perspective view thereof; and,

FIG. 10 is a top, front, and left side perspective view thereof, with an unclaimed handle shown in broken lines.

The broken lines in the drawings depict probable environment only and form no part of the claimed design.
